DESIGN FOR A TABLE LAMP

Alfred I. Alter, Wilton, Conn., assignor to Alfred Alter Company, New York, N. Y., a co-partnership

Application October 12, 1945, Serial No. 122,799

Term of patent 3½ years

(Cl. D48—20)

To all whom it may concern:

Be it known that I, Alfred I. Alter, a citizen of the United States, residing at Wilton, in the county of Fairfield and State of Connecticut, have invented a new, original, and ornamental Design for a Table Lamp, of which the following is a specification, reference being had to the accompanying drawing, forming part thereof.

In the drawing:

Fig. 1 is a front perspective view of a table lamp, showing my new design;

Fig. 2 is a rear perspective view thereof.

The dominant features of my design reside in the portions shown in full lines.

I claim:

The ornamental design for a table lamp, substantially as shown and described.

ALFRED I. ALTER.
